W. J. WHITACRE

WALL OR BACKPLATE FOR ELECTRIC LIGHTING FIXTURES

Filed Nov. 12, 1924

INVENTOR

William J. Whitacre,
BY *John Elias Jones,*
ATTORNEY

UNITED STATES PATENT OFFICE.

WILLIAM J. WHITACRE, OF CINCINNATI, OHIO.

DESIGN FOR A WALL OR BACKPLATE FOR ELECTRIC-LIGHTING FIXTURES.

Application filed November 12, 1924. Serial No. 11,349. Term of patent 3½ years.

To all whom it may concern:

Be it known that I, WILLIAM J. WHITACRE, a citizen of the United States of America, residing at Cincinnati, in the county of Hamilton and State of Ohio, have invented a new, original, and ornamental Design for Wall or Backplates for Electric-Lighting Fixtures, of which the following is a specification, reference being had to the accompanying drawing, forming part thereof.

In the said drawing, the view presented

is a front elevation of a wall or backplate used in connection with candelabrum or other illuminating parts of electric-lighting bracket fixtures and embodying my new and original design, taken both in detail and ensemble and principally for front display.

I claim:

The ornamental design for a wall or backplate for electric-lighting fixtures, as shown and described.

WILLIAM J. WHITACRE.
